Des. 187,667
Patented Apr. 12, 1960

187,667

PNEUMATIC GAUGE FOR MEASURING SIZES, DIMENSIONS AND THE LIKE

Nelson Emmons III, Dayton, Ohio, assignor to The Sheffield Corporation, Dayton, Ohio, a corporation of Delaware

Application July 3, 1958, Serial No. 51,647

Term of patent 14 years

(Cl. D52—1)

FIG.1

FIG.2

FIG.4

FIG.3

Figure 1 is a front perspective view of a pneumatic gauge for measuring sizes, dimensions, and the like showing my new design,

Figure 2 is a rear perspective view thereof,

Figure 3 is a top plan view, and

Figure 4 is a fragmentary sectional view taken along line 4-4 of Figure 2.

I claim:

The ornamental design for a pneumatic gauge for

measuring sizes, dimensions and the like, substantially as shown.
